United States Patent Office

Des. 191,556
Patented Oct. 10, 1961

191,556

PENCIL SHARPENER

Jack Fairchild Fleming, Summit, and Otto Lehre, Springfield, N.J., assignors to Sterling Plastics Co., Union, N.J., a corporation of New Jersey

Filed Sept. 28, 1960, Ser. No. 62,449

Term of patent 14 years

(Cl. D74—21)

Fig. 1

Fig. 2

Fig. 3

FIG. 1 is a side perspective view of a pencil sharpener embodying our new design, the opposite side thereof being substantially identical;

FIG. 2 is a front end elevational view; and

FIG. 3 is a rear end elevational view thereof.

The stippling on the drawing indicates contrasting portions.

We claim:

The ornamental design for a pencil sharpener, substantially as shown and described.
